SOLDERLESS CONNECTER

Harrison J. L. Frank, Detroit, Mich., assignor to
 Bulldog Electric Products Company, Detroit,
 Mich., a corporation of West Virginia

Application August 4, 1934, Serial No. 738,448

8 Claims. (Cl. 173—259)

This application relates to electrical connectors and particularly to those used for effecting mechanical and electrical connection of a cable terminal to electrical apparatus, such as a connection strap, bus bar, or the like, without the use of solder, and therefore known as solderless connectors.

For years it was common practice to connect cable terminals to electrical apparatus by means of cable terminal lugs of the type comprising a tubular element receiving the cable terminal, and in which the cable terminal was securely fastened by means of solder, the lug in turn being connected to the apparatus by means of a screw or the like. The use of such connectors has for some time been regarded with disfavor and it has often been attempted to devise satisfactory solderless connectors. The results of these attempts, while to certain extents satisfactory, have generally been found unsatisfactory, because the connectors devised up to now were such that there could be no assurance that the cable terminal was properly mechanically secured and electrically connected to the apparatus; and also because these connectors were designed for and could connect only one size of wire.

By the present invention, there are provided solderless connectors for cable terminals which are more efficient for the purposes of securing cable terminals in proper mechanical and electrical connection than solderless connectors heretofore known.

A principal characteristic that distinguishes the connector of this application from connectors heretofore known is the characteristic that the cable terminal is secured in the connector, not by pressure clamping alone, as is the case with many connectors now known, but, in addition, by an interlock forming shear or bite action which is much more satisfactory for the purposes intended.

One form of connector is shown in the appended drawing, and this form will be described in detail with reference to this drawing.

In the drawing,

Figures 1 and 2 show in sectional elevation and side view one type of connector.

The connector of Figures 1 and 2 comprises a sheet metal strap bent to form a U having opposite sides 10, a bight 12, and an extension 14, by means of which the connector may be attached to a bus bar 15 or the like through screw 16. The opposite sides of the connector are provided with alined partially cut slots 17, and the tongues 18 and 19 formed by these slots are bent in from

opposite sides of the connector at different levels thereof to form a pair of clamping surfaces between which may be passed the terminal 20 of a cable 21. A screw 22 is threadedly secured in the bight 12 and may be tightened down to move the clamping tongue 18 towards the clamping tongue 19 in a manner to securely clamp the terminal 20 in and to the connector. The tongue 19 bridges the sides 10 so that these sides form abutments for the tongue 18.

One action resulting from tightening down the screw 22 is a clamping action. In the connector shown, the clamping action is aided by an interlock which is provided by virtue of the provision of male and female formations 23—24 in the tongues 18—19, the formations distorting the terminal to prevent easy withdrawal thereof from the connector. If desired, the formations may be omitted, in which case clamping action alone may be relied upon to secure the terminal 20 properly.

Now having described one embodiment of the invention, reference is had to the following claims which determine the scope thereof.

What I claim is:

1. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides.

2. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides, and a screw passing through the bight of the U and manipulable for urging one of said tongues towards the other to clamp a cable terminal therebetween.

3. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides, at least one of the tongues having a deformation for deforming the terminal clamped thereby.

4. A cable terminal connector comprising a

- strap bent to provide a U having opposite sides and a bight, tongues cut from said sides to provide alined apertures therein and bent inwardly of the U at different levels to provide clamping parts which may receive between them a cable terminal passed through the alined apertures of the connector sides, one of the tongues bridging the connector sides so that both sides form abutments for this tongue.
5. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides, at least one of the tongues having a deformation for deforming the terminal clamped thereby, and a screw passing through the bight of the U and manipulable for urging one of said tongues towards the other to clamp a cable terminal therebetween, one of the tongues 15 bridging the connector sides so that both sides form abutments for this tongue.
10. 6. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides, and a screw passing through the bight of the U and manipulable for urging one of said tongues towards the other to clamp a cable terminal therebetween, the tongue not so urged 20 by the screw bridging the connector sides so that both sides form abutments for this tongue.
15. 7. A cable terminal connector comprising a strap bent to provide a U having opposite sides and a bight, tongues cut from said sides to provide alined apertures therein and bent inwardly of the U at different levels to provide clamping parts which may receive between them a cable terminal passed through the alined apertures of the connector sides, at least one of the tongues 25 having a deformation for deforming the terminal clamped thereby, and a screw passing through the bight of the U and manipulable for urging one of said tongues towards the other to clamp a cable terminal therebetween, the tongue not so urged 30 by the screw bridging the connector sides so that both sides form abutments for this tongue.

HARRISON J. L. FRANK.

CERTIFICATE OF CORRECTION.

Patent No. 2,015,177.

September 24, 1935.

HARRISON J. L. FRANK.

It is hereby certified that error appears in the printed specification of the above numbered patent requiring correction as follows: Page 2, second column, line 25, claim 8, for "connected" read connector; and that the said Letters Patent should be read with this correction therein that the same may conform to the record of the case in the Patent Office.

Signed and sealed this 5th day of November, A. D. 1935.
